UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

DIFFERENTIAL MICROPHONE-TRANSMITTER.

1,033,085.

Specification of Letters Patent.

Patented July 23, 1912.

Application filed October 24, 1910. Serial No. 588,787.

To all whom it may concern:

Be it known that I, JOHN J. COMER, a citizen of the United States of America, and resident of Chicago, Cook county, Illinois, have invented a certain new and useful Improvement in Differential Microphone-Transmitters, of which the following is a specification.

My invention relates to telephone transmitters of the kind ordinarily known as differential transmitters.

Generally stated, the object of my invention is to provide an improved and highly efficient form of differential transmitter adapted more particularly for use in loud speaking telephone systems, or in loud transmission systems for music, as in such systems heavy currents are often necessary, and purity of tone and clearness of enunciation are important and desirable.

It is also an object to provide a construction which will be simple and economical to manufacture, which will facilitate the assembling of the parts, and which will afford easy access thereto, for various purposes, as, for example, in filling the microphone box with granular carbon or similar material.

To these and other useful ends, my invention consists in matters hereinafter set forth and claimed.

In the accompanying drawings—Figure 1 is a longitudinal section of a differential microphone transmitter embodying the principles of my invention. Fig. 2 is a rear elevation of the said transmitter with the casing thereof removed to show the microphone. Fig. 3 is a perspective of the different parts of the microphone. Fig. 4 is a view similar to Fig. 1, showing another form of my invention. Fig. 5 is a rear view (similar to Fig. 2) of the transmitter shown in Fig. 4. Fig. 6 is a perspective (similar to Fig. 3) of the parts of the microphone shown in Figs. 2, 4 and 5.

As thus illustrated, and referring to Figs. 1 to 3, inclusive, my invention comprises a front plate A having a central aperture a' for the usual mouth piece a' . The metal diaphragm B is insulated from the plate A and held in place by a disk C, which latter has a perimeter or edge c that bears against the diaphragm, to hold the same in place, and a central aperture c' . The insulation c^2 is applied to the edge portion of

the disk C, and a clamping ring D has a rib d that bears against the insulation to firmly clamp the disk C and diaphragm together and against the shoulder a^2 on the inside of the plate A, but with insulation a^3 separating the diaphragm from the plate A. The ring D has a screw threaded edge d' that engages the threads d^2 on the inside of the plate A.

The differential microphone E comprises a lava ring e , a back carbon disk or electrode e' closing the rear end of said ring, a metal terminal disk or plate e^2 separating said electrode from the mica disk or plate e^3 , and a back plate or metal clamping disk e^4 bearing against said mica disk. The front of the ring is closed by a disk of carbon e^5 , which serves as the front electrode, a metal terminal disk or plate e^6 bearing against the said front electrode, and a mica disk e^7 bearing against and covering said metal disk. The clamping or binding screws e^8 extend through all said electrodes and disks of the box thus formed, and through the lava ring e , and into the disk C at points 80 around the openings c' in the center thereof. The plunger e^9 is of carbon, and is disposed centrally of the interior of the box, and is connected by a stem e^{10} with the center of the diaphragm. This stem extends 85 through holes e^{11} in the front electrode e^5 and the mica disk e^7 , which holes are closed around the stem with fluffy asbestos or other suitable material. The ring e has a lateral hole e^{12} for the introduction of the granular 90 carbon e^{13} into the interior of the microphone box after the same is fully assembled. This is easily done as the said box is disposed on the back of the disk C and is easily assembled.

The back of the transmitter is closed by a cap or cover F in the usual manner.

In use one terminal wire goes to the plate or disk C, another goes to the terminal plate e^2 and the third goes to the terminal plate e^6 , the circuits being of any suitable character.

The construction of the transmitter is simple and strong and facilitates assembling of the different parts. Also, the construction 105 of the microphone box permits the use of heavy currents, and the raising of the box to a high temperature, without danger. This is important, as in loud transmission such currents are often necessary, and in 110

such case the ordinary transmitter will not answer. A differential transmitter, such as described, is especially adapted for loud transmission, either for speaking or for music.

The construction in Figs. 4 to 6, inclusive, is practically the same as that previously described. In this case, however, the central or middle electrode G is not connected to the middle of the diaphragm H, but is connected by four spider arms g with the said diaphragm at points on the latter equidistant from the center thereof. Also, in this case, the ring I is made in two parts, i and i', which leave openings i² between them for the arms g. These arms extend through openings g' in the clamping plate J, which latter corresponds to the clamping plate C of the previously described construction. Thus the amplitude of vibration of the electrode G is not as great as that of e², but the vibration is somewhat more powerful, and the center of the diaphragm is left free and clear to receive the vibrations. The vibration is a little more powerful this way, because the diaphragm is used as a lever, the connection to the electrode G being between the fulcrum and the power, the rim of the diaphragm being the fulcrum, and the power being applied at the center of the diaphragm where the vibrations impinge thereon.

Thus it will be seen that by my invention I provide a differential microphone transmitter of high efficiency and adapted for use in loud transmission systems.

What I claim as my invention is:

1. In a transmitter, a diaphragm, a plate bearing against the margin of said diaphragm, to hold the latter in place, a differential microphone on the back of said plate, and connections between said diaphragm and microphone, which connections are eccentric of the diaphragm.
2. In a transmitter, a diaphragm, a stationary differential microphone, and a plu-

rality of connections from said microphone to said diaphragm, said connections eccentric of the diaphragm.

3. In a transmitter, a diaphragm, a clamping disk therefor, a pair of stationary electrodes, a ring for spacing said electrodes apart, a metal plate back of each electrode, a mica plate outside of each metal plate, screws extending through said ring and electrodes and plates, and into said disk, to clamp the same upon the said disk, a movable electrode between said electrodes, granular carbon between all said electrodes, and means connecting said movable electrode with said diaphragm.

4. In a transmitter, a diaphragm, a differential microphone including a pair of stationary electrodes and a movable electrode located between said stationary electrodes, and connections from said movable electrode to said diaphragm at points eccentric of said diaphragm.

5. In a transmitter, a diaphragm, a carbon box, a pair of stationary electrodes mounted in opposite ends of said box, a movable electrode located between said stationary electrodes, and connections from said movable electrode passing through the sides of said box to said diaphragm at points eccentric of the same.

6. In a transmitter, a diaphragm, a plate bearing against the margin of said diaphragm, and a differential microphone mounted on the back of said plate, said microphone including a pair of stationary electrodes and a movable electrode located between said stationary electrodes, and connections from said movable electrode to said diaphragm at points eccentric of said diaphragm.

Signed by me at Chicago, Illinois, this 12th day of October, 1910.

JOHN J. COMER.
